UNITED STATES PATENT OFFICE

2,057,487

BINDER

Russell C. Hill, San Antonio, Tex.

Application September 30, 1935, Serial No. 42,790

2 Claims. (Cl. 281—19)

The invention relates to improvements in binders especially adapted for use in binding leaves into book form, the primary object of the invention being the provision of a simple arrangement of the character indicated which is capable of economical production and highly efficient in use.

Other objects will appear hereinafter.

The invention consists in the combinations and arrangements of parts hereinafter described and claimed.

The invention will be best understood by reference to the accompanying drawing forming a part of this specification, and in which

Fig. 1 is a partial perspective view of a binder embodying the invention;

Fig. 2 an enlarged partial transverse section of the same;

Fig. 3 a section taken substantially on line 3—3 of Fig. 2; and

Fig. 4 a view similar to Fig. 3 but showing a slightly modified form of construction.

The embodiment of the invention illustrated in the drawing comprises a suitable flexible cover member 10 having a binding element in the form of a sheet metal plate 11 rigidly secured thereto and to a cooperating reinforcing bar 12 by means of rivets 13 passing through said cover member as shown. The ends 14 and 15 of the plate 11 are bent upwardly as indicated, the end 14 being doubled upon itself at 16, and a resilient binding tongue 17 formed integrally therewith and arranged to traverse the space between the ends 14 and 15 below the tops thereof. The binding tongue 17 is thus adapted and arranged to be threaded through the coils 18 of a helical wire binding for the loose leaf sheets 19, as will be readily understood. As indicated, the ends 14 and 15 will

thus be caused to embrace the edges of the leaves or sheets 19, thereby preventing lateral displacements thereof and holding said sheets in nice registration or alinement with each other. The end 15 is provided with a bayonet slot 20 into which the end of the tongue 17 may be engaged after it has been threaded through the coils 18. As will be noted, the entry opening to the slot 20 is in the side of the end member 15 and the locking notch of the slot is arranged at the top thereof, so that the resiliency of the tongue 17 will cause the end of the tongue to interlock in said notch and thereby hold said tongue against disengagement with the end member 15.

By this arrangement a simple and effective

binder is provided which may be readily employed for detachably binding or securing sheets in book form to a cover; which will nicely hold the bound sheets or leaves in place by preventing lateral displacement thereof; which will permit of easy removal or replacement of said sheets; which will so reinforce the flexible cover members as to avoid any additional covers for stiffening, reinforcing or strengthening the same; which may be readily employed in conjunction with helical or spiral wire bindings or metal loops or rings and will enclose and guard the same to prevent damage or marring of desk tops, table tops, or other finished surfaces; which is compact in form and neat in appearance; and which is capable of economical production.

In the modification illustrated in Fig. 4, the binding plate 11' is arched or curved as shown; both ends thereof are slightly different in shape, being given a rounded shape as indicated by the end 15'; the binding tongue 17' is in the form of a rod instead of a bar or strip; and the bayonet slot 20' is of slightly different form. Otherwise the construction and arrangement is the same as that already indicated; these modifications somewhat improving the appearance of the binding when in use.

While I have illustrated and described the preferred forms of construction for carrying my invention into effect, these are capable of variation and modification without departing from the spirit of the invention. I therefore do not wish to be limited to the precise details disclosed but desire to avail myself of such modifications and variations as fall within the scope of the appended claims.

I claim:

1. A binder comprising a cover member; a binding element in the form of a sheet metal plate secured centrally to said cover member, the ends of said plate being turned upwardly and being adapted to embrace the ends of leaves inserted therebetween; and a resilient binding tongue formed integrally with one of the ends of said plate and traversing the space between said ends below the tops thereof and detachably connected with the other end of said plate, there being a bayonet slot in said other end to receive the end of said tongue, said slot being arranged relatively to the resiliency in said tongue to cause said resiliency to effect interlocking between the tongue and slot.

2. A binder comprising a cover member; a binding element in the form of a sheet metal

plate secured centrally to said cover member, the ends of said plate being turned upwardly and being adapted to embrace the ends of leaves inserted therebetween, the extremity of one of said ends being doubled inwardly and downwardly upon itself; and a resilient binding tongue formed integrally with the inner end of said doubled-back extremity and traversing the

space between said ends below the top thereof, there being a bayonet slot in the other end to receive the end of said tongue, said slot being arranged relatively to the resiliency in said tongue to cause said resiliency to effect interlocking between the tongue and slot. 5
